Primary Examiner — Rebecca Tsehay

(57) **CLAIM**

The ornamental design for a power supply device for an electronic atomizing device, as shown and described.

DESCRIPTION

FIG. 1 is a perspective view of a power supply device for an electronic atomizing device;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof; and,

FIG. 8 is an enlarged bottom plan view thereof.

The broken lines in the drawings depict portions of the power supply device for an electronic atomizing device that form no part of the claimed design.

1 Claim, 8 Drawing Sheets
